UNITED STATES PATENT OFFICE.

WALTER J. GADSBY, OF BOSTON, MASSACHUSETTS, ASSIGNOR TO THE ROXBURY CARPET COMPANY, OF SAME PLACE.

DESIGN FOR CARPETS.

SPECIFICATION forming part of Design No. 11,775, dated May 11, 1880.

Application filed April 15, 1880. Term of patent 3½ years.

To all whom it may concern:

Be it known that I, WALTER J. GADSBY, a subject of the Queen of Great Britain, residing at Boston, in the county of Suffolk and State of Massachusetts, have invented a new and original Design for Carpets, of which the following is a specification.

My present design is fully illustrated in the accompanying photograph, forming part of this specification.

It consists in the light-ground centers c c', occurring at regular intervals, and surrounded by floral ornamentation consisting of combinations of natural flowers and foliage in free hand upon a plain background.

I claim—

The design for a carpet herein shown and described, consisting in the light-ground centers c c', occurring at regular intervals and surrounded by floral ornamentation consisting of combinations of natural flowers and foliage in free hand upon a plain background.

In testimony whereof I have signed my name to this specification, in the presence of two subscribing witnesses, this 13th day of April, A. D. 1880.

WALTER J. GADSBY.
